Primary Examiner — Jennifer Rivard*Assistant Examiner* — Alison M Ofstun(74) *Attorney, Agent, or Firm* — Lathrop Gage LLP(57) **CLAIM**

The ornamental design for a mount for electronic devices, as shown and described.

DESCRIPTION

FIG. 1 is a front perspective view of a mount for electronic devices showing our new design;

FIG. 2 is a front elevational view of the mount for electronic devices of FIG. 1;

FIG. 3 is a rear elevational view of the mount for electronic devices of FIG. 1;

FIG. 4 is a right-side elevational view of the mount for electronic devices of FIG. 1;

FIG. 5 is a left-side elevational view of the mount for electronic devices of FIG. 1;

FIG. 6 is a top plan view of the mount for electronic devices of FIG. 1; and,

FIG. 7 is a bottom plan view of the mount for electronic devices of FIG. 1.

The broken lines are shown for the purpose of illustrating portions of the article that form no part of the claim.

1 Claim, 7 Drawing Sheets(56)
